HAIR DRYING PROCESS

Charles Albert Phipps, Hartsdale, N. Y.

Application December 16, 1941, Serial No. 423,138

14 Claims.

(Cl. 34—3)

This invention relates to an improved process for drying hair on the human head. It relates more specifically to the drying of women's hair in a manner which will eliminate the discomfort of present methods.

One of the objects of this invention is to provide a process for drying women's hair in a greatly reduced time.

Another object of this invention is to provide a process for drying women's hair in a cycle which can at all times be adjusted to the maximum comfort of the subject, and which is not limited to the degree of comfort obtainable by the temperature and humidity limitations of the prior methods.

Another object of this invention is to provide a process for drying women's hair in which the most favorable conditions for drying the hair with speed and comfort are maintained independently of atmospheric conditions.

A further object of this invention is to provide a process for drying women's hair by the use of air of reduced moisture content, without danger of introducing chemical agents into the hair.

This invention provides a process for drying women's hair quickly while permitting the subject to control the comfort of the operation, so that there is no feeling of excessive heat at any time during the process. It also provides, as part of the same process, a greatly reduced time of drying, so as to further increase the comfort and convenience of the operation.

This invention also provides a process in which air of a higher temperature than is now generally used can be employed without discomfort to the subject; and in which air of lower temperature than is now generally used can be obtained by a simple adjustment, while maintaining under both conditions a higher rate of evaporation than is ordinarily obtainable under conditions giving a comparable amount of comfort.

The hair dryers in general use are of several basic types. In the most common type, air is heated by any convenient means and is blown on the hair with considerable force, after which the said air is allowed to escape. This type of dryer has the disadvantage that it relies wholly upon the increased temperature and velocity of the air to obtain its drying effect. The amount of moisture present in the atmospheric air may, at times, approach the saturation point at room temperature under very humid conditions, and the drying properties of this air when heated are accordingly severely limited under the very conditions which produce maximum discomfort to the

subject. The time of drying is thus unduly prolonged under these conditions, adding to the discomfort.

Another type of dryer in general use recirculates the major part of the air so that it is used again and again, thus avoiding the continuous heating of new atmospheric air. Although this reduces somewhat the cost of operation, it still further reduces the drying properties of the air in a progressive manner, as moisture is evaporated from the hair and recirculated with the air. Although the cumulative effect of adding moisture to the recirculated air is partially offset in some dryers by bringing in additional atmospheric air to replace a part of the moisture-laden recirculated air, the over-all effect in dryers of this type is to increase the drying time and decrease the comfort of the subject by blowing increasingly moisture-laden air onto the hair during all or a large part of the drying process. This type of dryer is also subject to the discomfort and increased drying time caused by humid atmospheric conditions.

An attempt has been made to correct these conditions by chemically dehydrating the air prior to blowing it onto the head of the subject. Several serious objections make this type of dryer commercially impracticable, and in so far as the applicant has been able to determine, it is not found in use. These objections are that it is not practical to absorb moisture chemically without incurring the danger of minute particles of chemical being deposited in the hair of the subject; that the chemical absorption of moisture liberates heat, making the drying operation uncomfortable; and that the chemicals become progressively saturated with moisture, so that, in the latter part of the drying operation, the absorption is less effective than in the earlier stages. Also, the need for changing chemicals is a nuisance, and the cost of these chemicals is not acceptable to the trade in view of their lack of practical benefits.

A more successful method of partially compensating for the above deficiencies of the present methods has been to produce higher effective air velocities in contact with the hair, and to improve the distribution of this air, so as to obtain increased rates of evaporation. However, a much more desirable method would be a process to obviate the above-mentioned deficiencies at their sources, and which would also utilize the improvements of high effective velocities and good distribution to obtain more rapid and comfortable drying of hair than has hitherto been

possible. The present invention accomplishes this new result.

The process by which this invention is carried out comprehends the continuous use of air from which a large part of the moisture content has been removed by refrigerating and reheating air, with means for controlling the temperature and humidity of the said air, but is preferably accomplished in an economical manner by apparatus described in my Patent No. 2,314,101, dated March 16, 1943, and in accordance with the schematic flow diagrams in the present application.

The term "moisture content of air" as used herein is intended to denote weight of water content per unit of dry air, and is synonymous with the term "absolute humidity."

I recognize the following different stages of the operation of drying wet hair on the human head, particularly after the usual "setting" of the hair by an operator: Firstly, an initial stage in which the hair is very wet and there is a maximum opportunity for the evaporation of water from the surface of the hair masses; secondly, an intermediate stage, in which the hair is nearly dry on the surface of the hair masses, but not within the said masses or on the scalp; and lastly, a final stage in which most of the hair and most of the scalp area are substantially dry, but in which there are a few places deep in the hair masses to which the air has not penetrated as rapidly as elsewhere, and which require additional time for drying. These three stages obviously blend one into the other, but are here separated for the purpose of clearly describing the process.

The process of the present invention can be carried out in two general ways, each of which is a great improvement over all preceding methods for drying women's hair.

In the simplest variation of this process, air of greatly reduced moisture content is provided continuously throughout all stages of the drying process, independently of the moisture content of the atmospheric air or of the amount of moisture removed from the hair. The temperature of this air is controlled so that, in the first stage of drying, a comparatively high temperature is maintained. This temperature is under the direct control of the subject, and will be as high as is consistent with her comfort. This temperature will preferably be no lower than, and may even be higher than the temperatures used in ordinary hair dryers with their accompanying discomfort, but these relatively high temperatures will not be uncomfortable to the subject in the present process due to the greatly increased cooling effect of evaporation caused by the use of air having a low moisture content. In this stage, the evaporation is from all surfaces to which the dry air penetrates, and is very rapid.

As the second stage of drying is entered, the temperature of the air is lowered slightly by the subject, but the moisture content of the air is maintained at approximately the same very low level. Such low moisture content is of great importance at this stage of the drying operation, being used to maintain comfort as the heated air penetrates to the scalp and into the hair masses. Less surface moisture is also available to prevent such penetration and to readily produce a cooling effect by evaporating. None of the older methods is capable of carrying out this important part of the present process. Chemical dehydrators are necessarily less capable of producing air of a reduced moisture content after a period of exposure to moisture-laden air. Other

systems are either at the mercy of room conditions, or, in the case of ordinary recirculatory systems, have by this time also picked up a quantity of moisture from the hair, and are less able to cool and dry the head than at the start of their operation. During this stage, the reduced temperature of my process is preferably still higher than could be used with a comparable amount of comfort in the systems using moisture-laden air, and the rate of evaporation is higher because of this higher temperature combined with the use of air of very low moisture content.

As the drying process continues into the third stage, dry areas of the scalp become sensitive to high temperatures, as there is no moisture remaining to be evaporated except from perspiration, and it is desirable to keep the subject sufficiently cool that perspiration will be negligible. As this stage is entered, the very low moisture content of the air is maintained, but the temperature is lowered still further, and may be approximately body temperature, or even lower, so that the subject is comfortable. As each individual reacts somewhat differently to temperature changes, this adjustment must necessarily be under the control or direction of the subject, and the process must be capable of producing any desired reduced temperature condition within the range of comfort. The rapid drying action during this stage depends almost wholly upon the continued use of air of very low moisture content, and it is impossible to produce this condition with any of the older methods. All methods using moisture-laden air are incapable of this result, as they rely on high temperature for their drying action. The chemical dehydrators are, by this time, definitely unable to produce their driest air at the very time when the present process depends almost entirely upon the use of air of a very low moisture content. Also, their increased temperature due to heat liberated during absorption of moisture prevents the cooling which is a very important part of the present process. The new result of comfortable and rapid drying during this last important stage is thus incapable of being produced by such means. The new process is accomplished by, and is the opposite of, all of the older processes.

In the variation described above, my process is particularly applicable to multi-hood dryers using a common air treating unit, which continuously provides air of a reduced moisture content to all of the hoods, the temperature in each hood being regulated by supplementary individual controls to accommodate the varying stages of drying of the several subjects.

In order to accomplish the simplified process above described, it is necessary that a refrigerating and reheating capacity be provided which is capable of maintaining a low moisture content of the air throughout the operation. As the cost of refrigerating equipment rises very rapidly with an increase of capacity, it is desirable to obtain the practical benefits of this new process with the smallest possible refrigerating unit. This can be accomplished by modifying the process so that it can be carried out in a second manner as follows:

During the first stage of drying, there is an abundance of moisture present on the exposed surface of the hair, where it can be easily reached. In this stage, low moisture content is not of as great importance as it is in the latter stages of the drying operation, as previously set forth. Also, a large volume of air may therefore be used

to better advantage than during the intermediate and final stages of drying. These conditions permit an economy in the capacity of refrigeration provided by enabling the refrigerating system to be designed so as to provide only an adequate volume of "dry" air for the important latter part of the operation, with air which is less dry being permitted in the earlier part of the operation. This permits recirculating part of the air withdrawn from the vicinity of the head or using a portion of atmospheric air without passing it through the refrigerating system. In this way a mixture of dried and undried air may be supplied to the head during the time when low moisture content is not critical, and a large volume of partially dry air is thus made available. In effect, when a recirculatory system is used such a mixture of dried and undried air is substantially of low moisture content, as a great part of the recirculated air withdrawn from the head does not carry with it a very large amount of moisture. In a closed system, it is desirable to reach a balance at a favorably low moisture content in which the rate of removal of moisture from the system is at least equal to the rate of moisture evaporation into the system, to prevent the accumulating of moisture.

The process, in this form, thus consists of supplying to the hair during the first stage of drying, air having a substantially reduced moisture content as compared with ordinary atmospheric air, at an elevated temperature, which may be as high as is compatible with the comfort of the subject. In the second stage of drying the temperature of the air is reduced slightly under control of the subject, as may be indicated by her sensitivity to the heat present, and the moisture content is also reduced in order to provide improved drying conditions and to increase the cooling effect of evaporation, thus making it unnecessary to effect a substantial reduction in temperature. In the final stage of drying, the moisture content of the air is lowered to a still smaller amount, and the temperature is lowered further under the control of the subject, so as to provide comfort for the substantially dry and heat-sensitive scalp areas, while providing rapid drying of the remaining moisture in the hair. It is of course recognized to be desirable to provide for an adequately high velocity of the air over the surface of the hair to be dried to produce efficient drying during all stages of this operation.

Further modifications of the process are described in connection with the flow diagrams.

The diagrams presented herewith are submitted as illustrations of suitable means for accomplishing the processes embodied in this invention. No attempt has been made to show structural form, as apparatus which accomplishes the process described herein may be readily designed by a person well versed in these arts.

Referring to the drawings,

Figure 1 is a diagrammatic illustration in sectional elevation of a device for drying women's hair with air which has been chilled to remove moisture therefrom, having controls to effect the process of the present invention.

Figure 2 is a diagrammatic illustration in sectional elevation of a modification of the device shown in Figure 1, provided with means for recirculating the air.

Figure 3 is a diagrammatic illustration in sectional elevation of a modification of the device shown in Figure 2, provided with means for bypassing the refrigerating unit with a part of the

recirculated air, in order to more economically put the process of the present invention into use.

Figure 4 is a diagrammatic illustration in sectional elevation of a modification of the device shown in Figure 3, for serving a plurality of hoods with a central refrigerating and heating system, embodying further modifications in the control of the process of the present invention.

It is intended that, as the specific control means are merely illustrative of the process, the control features shown in the various figures may be interchanged as may be required to meet the problems of economical design, and that other control devices not illustrated may be used, as long as they are capable of making the process of the present invention effectual.

Referring to Figure 1 in greater detail, air is drawn by a pump, fan or the like, such as the blower 1, by means of a tube or duct 46, through a cooling zone 2 which may pass through a tank 3 containing cold heat-conductive fluid such as chilled brine. The air cooling zone 2 may be chilled by any suitable means involving direct or indirect heat exchange. A preferred method is to use a refrigeration cycle of any of the conventional types having separate heat absorption and heat dissipation areas. For example only, and for convenience, the single refrigerant compression-evaporation cycle is illustrated in the drawings, although the invention may also be used with absorption type and with three-component refrigeration systems such as the Electrolux cycle, or the like. For example, a suitable refrigerant may be compressed by compressor 12, condensed in heat dissipating coils 7 and 42, passed by line 13 through expansion valve 14 into heat absorption coil 15, from which it is passed by line 16 back to the compressor.

The water condensing from the air in zone 2 is removed from duct 4 by pipe 5 which may be provided with trap 6 to permit automatic operation without leakage of air. The chilled air leaving the cooling zone is directed by duct 4 over heating surfaces indicated at 7. Heating unit 7 may be part of the condenser of a refrigerating cycle used to chill the brine in tank 3, and may be provided with an adjustable throttle or valve 41 to control the flow of refrigerant therethrough. Another part of the condenser of the refrigerating cycle, indicated at 42, may be used to dissipate excess heat from the refrigerating system such as that due to the continuous cooling of atmospheric air and the removal of moisture therefrom, the heat to be dissipated being generally greater than that needed for reheating the air by heating unit 7 under most conditions of operation. Throttle or valve 43 may be used in conjunction with valve 41 to regulate the flow of refrigerant through the two parts of the condenser 42 and 7, as a means for controlling the amount of heat liberated into the air passing through duct 4, and in this way adjusting the temperature of the air leaving the cooling and heating apparatus. These valves may be linked to a common control or handle of any convenient type, to simultaneously partially open one valve while partially closing the other, so as to permit convenient operation of this control means by the subject whose hair is being dried.

A by-pass valve or vane 21 is provided to permit a mixture of atmospheric air with cooled and reheated air at such times as the process is furthered thereby or the operation of the process is made more economical, as would be the case, for example, under conditions of substantially dry

atmospheric air. Blower 1 passes the total flow of such air under increased pressure over heating element 8, which may be an auxiliary heater of any desired type, such as a steam or gas coil or an electrically heated element which is controllable by means of suitable valves, switches or rheostats 44. Such control means is preferably arranged to be conveniently operated by the subject, and may be linked with a common control or handle provided for valves 43 and 41. This linkage may be direct, so that the auxiliary heating element 8 is made effective when the handle is turned to a position for increased temperature, or the linkage may be made through an adjustable thermostatic control 45, so that the auxiliary heating element will only be operative when the desired temperature is not produced by heating element 7.

The arrangement illustrated in Figure 1 may be used to make the present process effective as follows: Air having a moisture content substantially below that of atmospheric air may be continuously produced by passing atmospheric air over the cooling and reheating elements 3 and 1, and withdrawing moisture at 5. This dried air may be mixed with a portion of undried atmospheric air by the use of bypass 21, or may be used without such admixture of atmospheric air, in either case providing a flow of air of reduced moisture content relative to the prevailing atmospheric air. The adjustment of valves 41 and 43, supplemented if necessary by the use of heating element 8, all under the control of the subject, provides a relatively high temperature of the air supplied to the head during the early part of the drying operation, compatible with the comfort of the subject. As drying progresses, and the cooling effect of evaporating liquid in the hair decreases, the temperature of the air supplied to the head is reduced under control of the subject by means of control element 44 of heating element 8, and by means of control valves 41 and 43, which reduce the dissipation of heat from heating element 7. The refrigerating of air for the removal of moisture continues, however, so that the moisture content of the air during the latter part of the drying operation may be maintained as low as in the initial stages, or may be lowered. If vane 21 is used during the early part of the drying operation to bypass atmospheric air around the cooling and reheating elements, it may be partially or entirely closed during the latter stages of drying, to assist in the production of drier air by forcing a greater portion of the air through the cooling and reheating operation.

In Figure 2, air withdrawn from the vicinity of the head through duct 10 to blower 1 is passed under pressure through cooling zone 2 and over heating elements 7 and 8 to hood 9, and is distributed with adequate velocity into contact with the hair to be dried. Heating element 8 may be controlled by the subject by means of valve or rheostat 44. In this arrangement, it is assumed that the heat dispersed into the atmospheric air from the various warm parts of the apparatus, such as the outer surface of hood 9, duct 10, blower 1, and pipe 13 is adequate to prevent an excess of heat being built up within the system from the continuous condensation of moisture in cooling zone 2, and from heat added to the system by heating element 8 and pump 12. The air leaving cooling zone 2 is partially heated by heating unit 7, and additional heat is provided by heating unit 8 under control of the subject whose hair is being dried, as may be required for the present process.

It is also desirable, in providing for the comfort of the subject, to avoid escape of warm air from the hood about her face and neck. This may be accomplished by maintaining a slightly sub-atmospheric pressure within the hood. Such reduced pressure will cause a small flow of atmospheric air into the hood, rather than escape of warm air from the hood, and may be provided in a substantially closed recirculatory system by venting a small quantity of air from the high pressure zone, as by vent 11 which may be suitably placed at or near the blower discharge, or at any part of the system where the pressure is greater than atmospheric.

The arrangement illustrated in Figure 2 may be used to make the present process effective as follows: Air having a moisture content substantially below that of atmospheric air may be produced by passing air within a recirculatory system through a cooling zone 2 to chill the air below its dew point, and thereafter over heating units 7 and 8, withdrawing the condensed moisture at 5. The resulting air of reduced moisture content may be passed with adequate velocity into contact with the hair to be dried by any suitable means such as hood 9, from which it may be withdrawn through duct 10 and recirculated by blower 1 through the system, thus providing a continuous supply of air having a substantially reduced moisture content throughout the drying operation. In the initial stage of drying, the temperature of the air supplied to the wet hair is warmed by heating units 7 and 8 to a substantially high temperature which is compatible with the comfort of the subject. As the drying progresses, and the cooling effect of evaporating liquid in the hair decreases, the temperature of the air supplied to the hair may be reduced under control of the subject by the adjustment of control 44 of heating unit 8. Throughout the drying, the moisture content of the air supplied to the hair of the subject may be maintained at a suitably low level, which may be as low as in the early stages of the drying operation, or lower.

In addition to the elements shown in Figure 2, Figure 3 illustrates a duct 20 through which recycled air may by-pass the cooling and reheating elements 2 and 1. This duct is provided with a control valve or vane 21 for regulating the quantity of air permitted to pass therethrough. This by-pass valve preferably will not be opened until the moisture content of the air within the system is sufficiently low to permit the desired drying action, and it will preferably not be opened thereafter sufficiently to permit the moisture content of the air to the hood to exceed such amount. This constitutes an effectual means for controlling the humidity of the air supplied to the hood. The use of the by-pass is also advantageous in permitting recirculation of air at a high rate with a minimum load on the refrigeration unit. Also, in actual practice, the air leaving the hood 19 will not be saturated with moisture, and it will be generally sufficient, after an adequately low level of moisture content has been reached within the system, to pass only sufficient air through the refrigerator to remove the increment of moisture picked up on each recirculation cycle. However, if desired, vane 21 can be adjusted to further reduce the moisture content during the drying operation, by causing an adequate volume of air to pass through the cooling and reheating zones.

The air treating unit illustrated in Figure 3 is designed to provide heat transfer between the

inlet and outlet to and from the cooling chamber 2, and is also designed so as to require a minimum of insulation. These improvements provide economy of operation and utilize heat transfer through the walls of the ducts to further the desired process, as is described in greater detail in my Patent No. 2,314,101, dated March 16, 1943. It is also desirable to provide suitable means for precipitating any entrained droplets of water from the air leaving the cooling zone 2. Suitable means may provide a quick change in direction of the air stream by baffles 22.

The arrangement illustrated in Figure 3 may be used to make the present invention effective in the same manner as that illustrated in Figure 2, and as follows: Air having a moisture content substantially below that of atmospheric air may be continuously produced by passing air within a recirculatory system through a cooling zone 2 where it is chilled below its dew point, and subsequently passing it over a heating element 7. Entrained droplets of water may be thrown out by baffles 22, and the condensed moisture may be withdrawn by suitable means 5. The continuous supply of dried air may be mixed with recirculated air from the vicinity of the head by opening vane 21. The mixture may be further heated to any desired elevated temperature, compatible with comfort, by supplementary heating element 8, such temperature being controlled by the subject whose hair is being dried by adjustment of control 44. The warm dry air may then be applied with adequate velocity to the hair of the subject by hood 30, and thereafter withdrawn to blower 1 through duct 10. In the initial stage of drying, the temperature of the air supplied to the head may be relatively high while being compatible with the comfort of the subject, due to the cooling effect of rapid evaporation of liquid from the hair by relatively dry air. As the drying progresses, less water is available for evaporating in the hair, and the effect of evaporating liquid decreases. The temperature of the air supplied to the head may then be reduced by the adjustment of control 44, so that the subject remains comfortable. Vane 21 may, for example, be left in a fixed adjustment throughout the drying operation, and the refrigeration unit operated continuously, with the result that the moisture content of the air supplied to the head during the latter part of the drying operation is maintained at a suitably low level, which may be as low as during the initial stage, and may be even lower due to the reduced rate of evaporation. An optional method of operation, especially valuable when the individual whose hair is being dried is particularly sensitive to the application of heat to the substantially dry scalp, is to reduce the flow of air through duct 20 during the latter part of the drying operation by adjustment of vane 21, thus forcing a greater portion of the recirculated air through the cooling and reheating apparatus and decreasing the moisture content of the air supplied to the head independently of the rate of evaporation of moisture from the hair. The capacities of the various parts of the system may be so arranged that, even with vane 21 completely shut, an adequate volume of substantially dry air is provided to hood 30 to produce the velocity necessary for rapid drying. Air of very low moisture content may thus be employed during the final stage of drying, and the temperature of the air supply may be lowered to meet the requirements of the most sensitive individual, while

maintaining a high rate of drying as compared with all former methods.

The further modification illustrated in Figure 4 shows a use of the present improved process in a single air treating unit serving a plurality of hoods, and illustrates additional means for controlling the temperature of the air supply.

It is generally desirable in a large system supplying a plurality of hoods to use two blowers 10 or a double-acting blower, in order to reduce the pressure drop and reduce the load that each blower is required to carry. For example, blowers 32 and 33 are shown in Figure 4 connected respectively to the inlet and the outlet of the refrigeration unit.

15 The by-pass 21 from blower 32, and air from the blower 33, discharge into the common air duct 34, which is used for supplying air to a plurality of hoods. The ducts leading to the individual hoods and the return ducts from these hoods are 20 preferably supplied with individual control valves or vanes 35. These vanes are used to regulate the quantity of air to the individual hood. The vanes in the ducts to any one hood will, of course, be closed when that hood is out of service. The two vanes in the ducts leading to and from the same hood are preferably connected together in some suitable manner, so that a balance between the air entering and leaving that hood will be 25 effected at any rate of flow. This balance desirably will provide for the return of a slightly greater amount of air than is supplied by the duct leading to that hood, thereby maintaining the desired slightly sub-atmospheric pressure in 30 the hood, the excess air drawn in being released through the vent 11. Provision will, of course, be made to care for the increased volume of the 35 returning air due to its decreased pressure. The vanes 35 will be adjusted to maintain this condition in all hoods in use. The hoods will be used in such a manner that the head or hair of the subject will not unduly obstruct either the air supply or air withdrawal passages.

35 The heat balance, particularly in the multiple unit system, may also require additional control features in order to permit optimum conditions of operation. For example, the temperature of air to the common supply duct 34 may suitably be the lowest temperature considered comfortable by 40 any subject. Additional heat may be supplied by heating element 8 to provide the required temperature in any individual hood, according to the present improved process. This extra heat thus supplied to the system must, of course, be removed by some suitable means. The heat transferred to the chilled air from the heat dissipating coil 7 is limited as described above and thus will generally be less than the heat removed by the refrigeration coil 15 in the brine tank 3, which 45 removes the extra heat supplied by the supplemental heating elements and by the condensation of moisture. This extra heat that must be dissipated by the refrigeration cycle may be released to the atmosphere by an additional coil 50 36 before the refrigerant reaches the expansion valve 14. Coil 36 will generally be of sufficiently large capacity to take care of any fluctuations that may occur in the operation of the coil 7, whether due to heat from supplemental heating elements, or an accumulation of heat within the 55 cycle from any other source.

Additional control features providing for increased flexibility of operation and effectively controlling the temperature and humidity are the 60 by-pass 37, operated by valve or vane 38, and

the by-pass 39, similarly operated by a valve or vane. In the event that the temperature rises to a higher point than desired in supply duct 34, this may be lowered by opening valve 38, thus passing cool air through the by-pass 37. This causes additional heat to be carried by the refrigerant from coil 7 to coil 36, and serves as a means of removing heat from the system. The opposite effect may be gained and the air temperature raised in duct 34 by opening the by-pass 39 and passing additional air over the heating coil 7. This withdraws additional heat from coil 7, preventing its dissipation from the system at coil 36. As it is generally desirable to maintain a constant temperature in the common air supply duct 34, valves 38 and 39 may be operated automatically by a suitable thermostat 45 in duct 34. Additional heat may be required as, for example, in case of a sudden increase in load, or at the start of operation of the system. Supplemental heating element 40 is shown for this purpose, and may also be under the control of thermostat 45. A filter is indicated at 23, for the purpose of cleaning the air.

The arrangement illustrated in Figure 4 may be used to make the present invention effective, as follows: A continuous supply of air of a moisture content substantially reduced below that of ordinary atmospheric air is provided to common supply duct 34 by the cooling and reheating of air at 2 and 7, respectively, with the removal of condensed moisture at 5. This air may be mixed with recirculated air from blower 32 through partially open vane 21, as the air returned from the hoods will ordinarily be of substantially reduced moisture content compared with atmospheric air, and a portion of such air may be reused. The system will preferably be operated so that a balance is maintained between the overall rate of evaporation of moisture into the system, and the rate of removal of moisture therefrom, at a satisfactorily low moisture content of the air.

In each individual hood, the air will be supplied with adequate velocity to aid in rapid drying throughout the operation. Initially, the substantially dry air will be supplied at a relatively high temperature which is compatible with the comfort of the subject, adequate heat being obtained from supplemental heating element 8. As the drying progresses, there is less moisture available for evaporating from the hair, and consequently the cooling effect of the evaporating moisture decreases. The temperature of the air supplied to the particular hood is then reduced by adjustment of control 44 of heating element 8 by the subject, while the moisture content of the air is maintained at least as low as during the early part of the drying operation. In the last stage of the drying operation, control 44 may finally be adjusted so that no additional heat is supplied by heating element 8, thus providing cool, substantially dry air for maximum comfort of the subject under conditions in which the scalp is particularly heat-sensitive, while maintaining adequate velocity of air and a comparatively rapid rate of removal of the remaining moisture from the hair.

It should be recognized that the foregoing description of my invention describes methods for drying the hair with maximum comfort in the shortest practicable time. However, it is to be recognized that substantial benefit in reduced drying time or increased comfort to the subject can be secured by the use of less efficient refrigeration or less stringent control of absolute humidity and temperature than is necessary for optimum results.

I claim:

1. A process for quickly drying hair wet with liquid on a person's head by means of an air supply of controlled temperature and absolute humidity, with comfort to the person, comprising initially circulating room air over a cooling means to remove moisture therefrom and to thereby lower the absolute humidity of the air, subsequently reheating the cooled air by passing it over a heating means, and circulating the reheated air in contact with the hair on the head to dry the hair; then as the drying of the hair progresses and the cooling effect of evaporating liquid from the hair decreases, reducing the temperature of the heating means to reduce the temperature of the air used for drying the hair, and controlling the cooling means to maintain the absolute humidity of the air used for drying the hair at least as low as that of the air used in the first part of the hair drying process.

2. In a process for drying hair wet with liquid on the human head by means of air circulated in a cycle including the hair and cooling and heating means for controlling the absolute humidity and temperature of the air passing into contact with the head, a method of operation for quickly drying the head of a person with comfort comprising initially passing the drying air over the cooling means to remove moisture therefrom, and to thereby lower the absolute humidity of the air, then reheating the cooled air by passing it over the heating means, and circulating the reheated air into contact with the hair at a temperature compatible with the person's comfort to dry the hair; then as the drying progresses and the cooling effect of evaporating liquid decreases, reducing the temperature of the heating means, thus reducing the temperature of the drying air to maintain comfort, while continuously recirculating air in the cycle over the cooling and heating means to remove additional moisture therefrom.

3. A process for quickly drying hair wet with liquid on a person's head by means of an air supply of controlled temperature and absolute humidity, with comfort to the person, comprising initially circulating room air over a cooling means to remove moisture therefrom and to thereby lower the absolute humidity of the air, subsequently reheating said air by passing it over a heating means, mixing uncooled room air with said reheated air, and passing the mixture in contact with the head to dry the hair; then as the drying of the hair progresses and the cooling effect of evaporating liquid from the hair decreases, reducing the temperature of the heating means, thus reducing the temperature of the air used for drying the hair, to maintain comfort, while continuously passing room air over the cooling and heating means to remove moisture and controlling the admixture of uncooled room air with the said reheated air to maintain a suitable rate of drying.

4. A process for quickly drying hair wet with liquid on a person's head by means of an air supply of controlled temperature and absolute humidity, with comfort to the person, comprising initially circulating at least a portion of said air supply over a refrigerating means to remove moisture therefrom and to thereby lower the absolute humidity of the air, subsequently reheating the air by passing it over a heating means

and circulating the air in contact with the hair at a temperature compatible with the person's comfort, to dry the hair; then as the drying progresses and the cooling effect of evaporating liquid from the hair decreases, reducing the temperature of the heating means to reduce the temperature of the air in contact with the hair, to maintain comfort, while continuously passing at least a portion of the air supply over the refrigerating and heating means to maintain a lowered absolute humidity of the said air circulated in contact with the hair.

5. A process for drying hair wet with liquid on the human head by means of air circulated in a cycle including the hair and refrigerating and heating means for controlling the temperature and absolute humidity of the air passing into contact with the head, comprising initially circulating air within the cycle over the refrigerating means to remove moisture therefrom and to thereby lower the absolute humidity of the air, subsequently reheating the air by passing it over the heating means, and circulating the reheated air in contact with the hair on the head to dry the hair; withdrawing moisture-laden air from contact with the hair and recirculating said moisture-laden air over the refrigerating and heating means and returning it again into contact with the hair; and as the drying progresses and the cooling effect of evaporating liquid decreases, reducing the temperature of the heating means, thereby reducing the temperature to which the air is heated, thus maintaining comfort, while controlling the refrigerating means to maintain a lowered absolute humidity of the said air circulated in contact with the hair.

6. A process for drying hair wet with liquid on the human head quickly and with comfort by means of air circulated in a cycle including the hair and refrigerating and heating means for controlling the temperature and absolute humidity of the air passing into contact with the head, comprising initially circulating air within the cycle over the refrigerating means to remove moisture therefrom and to thereby reduce the absolute humidity of the air, subsequently reheating the cooled air by passing it over the heating means, and circulating the reheated air in contact with the hair on the head to dry the hair; withdrawing the moisture-laden air from contact with the hair and recirculating said moisture-laden air over the refrigerating and heating means and returning it again into contact with the hair; and as the drying progresses and the cooling effect of evaporating liquid in the hair decreases, reducing the temperature of the heating means, thereby reducing the temperature to which the air passing into contact with the hair is heated, thus maintaining comfort, and also controlling the refrigerating means to further reduce the absolute humidity of the air to maintain a high rate of drying.

7. A process for drying hair wet with liquid on the human head quickly and with comfort by means of air circulated in a cycle including the hair and refrigerating and heating means for controlling the temperature and absolute humidity of the air passing into contact with the head, comprising initially passing into contact with the hair, warm air of a temperature compatible with the person's comfort, and of absolute humidity substantially less than saturated air at that temperature; withdrawing the air from contact with the hair; dividing said air into two streams; cooling one stream to cause condensa-

tion of moisture therefrom by passing the air over said refrigerating means, and removing the condensed moisture; then applying such heat as may be required to said stream by passing the air over

5 said heating means; then mixing the resulting heated air with the uncooled withdrawn air in the other stream, and returning the warm mixture in the cycle into contact with the hair; then as the drying progresses and the cooling effect of evaporating liquid from the hair decreases, reducing the temperature of the air passing into contact with the hair by controlling said heating means, thus maintaining comfort, while maintaining the absolute humidity of the air substantially below that of saturated air at the new temperature by controlling the relative proportions of air in the two streams, to maintain a high rate of drying.

8. A process for drying hair wet with liquid on 20 the human head quickly and with comfort by means of air circulated in a cycle including the hair and refrigerating and heating means for controlling the temperature and absolute humidity of the air passing into contact with the head, 25 comprising initially passing into contact with the hair, warm air of a temperature compatible with the person's comfort, and of absolute humidity substantially less than that of saturated air at that temperature; withdrawing the air from contact with the hair; dividing said air into two streams; cooling one stream to cause condensation of moisture therefrom by passing the air over said refrigerating means, and removing the condensed moisture; then applying such heat as 30 may be required to said stream by passing the air over said heating means; then mixing the resulting heated air with the uncooled withdrawn air in the other stream, and returning the warm mixture into contact with the hair; then as the 35 drying progresses and the cooling effect of evaporating liquid from the hair decreases, reducing the temperature of the air passing into contact with the hair by controlling said heating means, thus maintaining comfort, while reducing the absolute humidity of the said air by controlling said 40 refrigerating means and controlling the relative proportions of air in the two streams, to maintain a high rate of drying.

9. A process for drying hair wet with liquid on 50 a person's head, comprising passing air in contact with refrigerating means to condense and remove moisture therefrom, thus reducing the absolute humidity of said air; subsequently passing at least a part of said air in contact with 55 heating means and by-passing the remaining part of said air around said heating means and combining said by-passed air and said heated air; subsequently passing said air over supplementary heating means and then into contact with the hair, evaporating moisture therefrom; withdrawing said air after contact with the hair and recirculating at least a part of said air in contact with said refrigerating means to remove additional moisture therefrom, and by-passing the remaining part of said air around said refrigerating and heating means, thus controlling the absolute humidity of said air; initially in said 60 drying process providing said air at a temperature compatible with the person's comfort, then as the drying progresses and the cooling effect of 65 evaporating liquid from the hair decreases, reducing the temperature of said air by adjusting the supplementary heating means to maintain comfort, while maintaining a suitably low absolute humidity of said air.

10. A process for drying hair wet with liquid on the human head by means of air passed in contact with refrigerating and heating means for controlling the temperature and absolute humidity of the air applied to the head, comprising initially withdrawing air from the room; dividing said air into two streams; cooling one stream by passing the air over said refrigerating means to cause condensation of moisture therefrom and to thereby lower the absolute humidity; removing the condensed moisture, and subsequently re-heating the cooled air by passing the air over said heating means; mixing the warm dehumidified air with the uncooled air in the other stream, and passing the mixture into contact with the hair at a temperature compatible with the person's comfort to dry the hair; then as the drying progresses and the cooling effect of evaporating liquid on the hair decreases, reducing the temperature of the heating means, thus reducing the temperature of the air passing into contact with the hair while maintaining a suitably reduced absolute humidity of said air by controlling the refrigerating means, thus maintaining comfort and a rapid rate of drying.

11. A process for quickly drying hair wet with liquid on a person's head by means of an air supply of controlled temperature and absolute humidity, with comfort to the person, comprising initially circulating at least a portion of said air supply over cooling means to condense and remove moisture therefrom, and to thereby reduce the absolute humidity of said air supply; subsequently circulating said air supply over heating means and then into contact with the hair at a temperature compatible with the person's comfort at that absolute humidity; then as the drying progresses and the cooling effect of evaporating liquid on the head decreases, maintaining a lowered absolute humidity of air supply by condensing additional moisture therefrom, while lowering the temperature of the heating means, thereby lowering the temperature of the air circulated in contact with the hair below the temperature used in the first part of the drying operation.

12. A process for drying hair wet with liquid on the human head quickly and with comfort by means of air circulated in a cycle including the hair and refrigerating and heating means for controlling the temperature and absolute humidity of the air passing into contact with the head, comprising initially passing into contact with the hair, warm air of a temperature compatible with the person's comfort and of an absolute humidity substantially less than that of saturated air at that temperature; withdrawing the air from contact with the hair; cooling it by passing said air in contact with the refrigerating means to cause condensation of moisture therefrom, and removing the condensed moisture; then dividing the air into two streams; supplying such heat to one

5 stream as may be required by passing the air over said heating means; then mixing the heated air with the unheated air in the other stream, and returning the mixture in the cycle into contact with the hair; then as the drying progresses and the cooling effect of evaporating liquid from the hair decreases, reducing the temperature of the air passing into contact with the hair by controlling the relative proportions of air in the two streams, thus maintaining comfort, while maintaining the absolute humidity of the air substantially below that of saturated air at the new temperature by controlling the said refrigerating means, thus maintaining a high rate of drying.

10 13. A process for drying hair wet with liquid on the human head quickly and with comfort by means of air circulated in a cycle including the hair and refrigerating and heating means for controlling the temperature and absolute humidity of the air passing into contact with the head, comprising initially passing into contact with the hair, warm air of a temperature compatible with the person's comfort and of an absolute humidity substantially less than that of saturated air at

20 that temperature; withdrawing the air from contact with the hair; then dividing the air into two streams; cooling one stream to condense moisture therefrom by passing the air over said refrigerating means; removing the condensed moisture; then mixing the cooled air with the other stream of uncooled air; then supplying such heat as may be required, by passing the air over said heating means and returning the mixture in the cycle into contact with the hair; then as the drying progresses and the cooling effect of evaporating liquid from the hair decreases, reducing the temperature of the air passing into contact with the hair by controlling said heating means, thus maintaining comfort, while maintaining the absolute humidity of the air substantially below that of saturated air at the new temperature by controlling the relative proportions of air in the two streams, thus maintaining a high rate of drying.

25 14. A process for quickly drying hair wet with liquid on a person's head by means of an air supply of controlled temperature and absolute humidity, with comfort to the person, comprising initially circulating room air over a cooling means to remove moisture therefrom and to thereby lower the absolute humidity of the air, subsequently reheating said air by passing it over a heating means, mixing uncooled room air with said reheated air, and passing the mixture in contact with the head to dry the hair; then as the drying of the hair progresses and the cooling effect of evaporating liquid from the hair decreases, controlling said heating means and the admixture of uncooled room air with said reheated air to reduce the temperature of said air used for drying the hair to maintain comfort.
